(57) **CLAIM**

The ornamental design for an arm for a clamp storage system, as shown and described.

DESCRIPTION

FIG. 1 is a perspective view of an arm for a clamp storage system showing a first embodiment of my new design;

FIG. 2 is a front end elevation view of the first embodiment;

FIG. 3 is a rear end elevation view of the first embodiment;

FIG. 4 is a top plan view of the first embodiment;

FIG. 5 is a bottom plan view of the first embodiment;

FIG. 6 is a first side elevation view of the first embodiment;

FIG. 7 is a second side elevation view of the first embodiment;

FIG. 8 is a perspective view of an arm for a clamp storage system showing a second embodiment of my new design;

FIG. 9 is a front end elevation view of the second embodiment;

FIG. 10 is a rear end elevation view of the second embodiment;

FIG. 11 is a top plan view of the second embodiment;

FIG. 12 is a bottom plan view of the second embodiment;

FIG. 13 is a first side elevation view of the second embodiment; and,

FIG. 14 is a second side elevation view of the second embodiment.

The broken lines in the figures depict portions of the arm for a clamp storage system that form no part of the claimed design.

1 Claim, 8 Drawing Sheets
